LOREN E. WELLS, OF MODESTO, CALIFORNIA

SAFETY HOOK

Application filed February 1, 1932. Serial No. 590,036.

This invention relates to hooks, and particularly to one especially adapted for use by linemen, as a detachable connection between the block and tackle and the come-along or wire engaging grip used when pulling wires.

In such operations the ordinary open hook of the tackle-block is engaged with the pull-link of the grip. When the pulling operation is completed the grip is disengaged and lowered to the ground with the tackle by means of a separate line attached to the grip or tackle hook. As the parts are at present constructed there is nothing to prevent the disengagement of the hook when the equipment is being thus lowered, and one or the other of the units are apt to come apart from the supporting line and drop to the ground, with grave danger of physical harm to the men standing on the ground below.

The principal object of my invention therefore is to eliminate the dangerous and objectionable features incident to the use of the ordinary type of hook on such equipment by providing a safety hook adapted to take the place of the ordinary block hook and so constructed that while it is easily associated with and removed from the link when desired, it cannot be so disengaged or removed by vibrations and jolting or jarring, or with any position which it may assume relative to the grip link when the grip is subject to the action of gravity and is hanging down on the hook.

Hooks made according to my invention have been tried out in actual practice and given severe tests under all possible conditions. From observations I can therefore truly state that it is practically impossible for the hook and link to become disengaged from each other under any working conditions which may obtain, unless it is intentionally desired to separate them.

A further object of the invention is to produce a simple and inexpensive device and yet one which will be exceedingly effective for the purpose for which it is designed.

These objects I accomplish by means of such structure and relative arrangement of

parts as will fully appear by a perusal of the following specification and claims.

In the drawing similar characters of reference indicate corresponding parts in the several views:

Fig. 1 is a longitudinal view of the hook shown in connection with a grip and a block and tackle arranged in outstretched pulling relation.

Fig. 2 is a perspective of the hook showing the same suspended from a lowering line and with the grip depending therefrom in one position.

Fig. 3 is a similar view showing the grip in another position.

Fig. 4 is a transverse section of the hook as on the line 4—4 of Fig. 1.

Fig. 5 is a longitudinal view of the hook showing the initial raising movement of the grip link necessary to disengage the same from the hook.

Fig. 6 is a similar view showing the final movement or adjustment of the link necessary in removing the same.

Referring now more particularly to the characters of reference on the drawing, the numeral 1 denotes a standard form of come-along or wire clamping tool having a link 2 projecting from one end and adapted for connection to a block and tackle 3. My safety hook which is permanently connected to the eye 4 of the tackle block in place of the usual hook is constructed as follows:

Said hook comprises first an eye 5 initially engaged with the eye 4 and then permanently closed. Beyond the eye the hook is formed with a substantially semi-circular bend forming an arch 6 disposed in a plane lengthwise of the hook but at right angles to the plane of the eye 5, and curved on a radius somewhat less than that of the bend of the link 2, as shown in Fig. 5. Beyond the bend the hook is formed with another eye 7 also lying in a plane lengthwise of the hook and at right angles to the plane of the eye 5, and symmetrically disposed relative thereto. The eye 7 is normally engaged by the link when the come-along and block and tackle are disposed in pulling relation to each other and to the hook. The eye 7 is not closed, however, and

its side opposite to that continuing from the bend 6 (which forms a connection between one side of the eye 7 and one side of the eye 5) passes behind said bend in clearance relation thereto a distance greater than the diameter of the link metal and forming a depending extension 8. At its lower or outer end the extension is bent at right angles to pass under the arch 6 as shown at 9 and is then bent up and over in the direction of said extension to form, with the portion 9, a hook 10 facing said extension.

This hook 10 lies in a transverse plane substantially at right angles to the plane of the eye 7, and its outer end is spaced from the extension a distance greater than the diameter of the link metal. Also the top of the hook 10 is symmetrically disposed relative to the axis of the arch 6 and the adjacent edges of said arch and hook are spaced from each other a distance somewhat greater than the thickness of the link metal as shown in Fig. 6. The hook 10 when in actual use only has to support the weight of the come-along and never takes any pulling strain. The metal of the main hook therefore may be gradually diminished in diameter where the eye 7 merges into the extension 8, so that the hook 10 is of relatively small diameter. This is also necessary in enabling the link to be removed, as will be hereinafter seen.

In operation, as long as the wire is being pulled the link is properly engaged with the eye 7 at its outer end. When it is desired to lower the come-along and tackle to the ground as a unit a lowering line 11 is connected to the eye 7, as shown in Fig. 2; the come-along being then disengaged from the wire so as to hang straight down. If the hook 40 is initially disposed so that the auxiliary hook 10 is under the arch, as shown in Fig. 1, the link when depending then abuts against the portion 9 of said hook 10, as shown in Fig. 2. This portion is wide enough to bear against both sides of the link and obviously no swaying of the link and tool relative to the hook will permit the link to move into the auxiliary hook and then to a position necessary for its removal, as shown in Fig. 6.

If the safety hook is normally disposed so that the auxiliary hook 10 is uppermost, the lowering line 11 is then naturally attached to the opposite side of the eye 7 relative to the normal position of the link. When the link depends from the hook therefore it has an opportunity with the swaying of the equipment to work down until it enters and is supported by the auxiliary hook 10, as shown in Fig. 3. The link will not then be detached by any jolting or swaying movement of the equipment, since in order to disengage the link from the hook it must first be disposed so as to extend lengthwise in a plane substantially parallel to the plane of the hook 10, raised so as to clear the upper portion of

said hook, and be then turned sideways so that its actual width is less than the diameter of the arch, as shown in Fig. 6. The link can then be withdrawn by a horizontal movement outwardly of the hook 10 or away from the extension 8.

While the above operation is easy enough to perform when the link and hook are being definitely and intentionally manipulated, it is obviously utterly impossible for the link 75 to assume of itself the necessary removing position relative to the hook 10, when said link is depending from this hook and is being constantly pulled down by the action of gravity. The relative thinness of the hook 10 is necessary to enable the link to be turned sideways without changing the link from its standard and somewhat narrow form and without making the arch unduly large, as would be necessary for it to conform to the 80 wider form of link if such were used. At the same time however, it will be obvious that if the safety hook is to be used with other tools having links of different relative size, the 85 arch and hook 10 would be changed in their dimensions if necessary so as to properly conform to those of the particular link used.

While I have here shown and described the eyes 4 and 7 as being disposed in planes at right angles to each other, such an arrangement is not actually essential, and the eyes may lie in a common plane if desired or found more suitable in certain kinds of service.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure 110 by Letters Patent is:

1. A safety hook comprising a closed eye adapted for permanent engagement with a block eye, another eye beyond the first eye for engagement with a link at its bend, a connection between and rigid with one side of the eyes, means formed with the second eye to enable the eye-engaging bend of the link to be moved about the latter and to assume a position below the connection without being disengaged from the hook, and means formed with said last named means and with the connection to permit of the removal of the link from its last named position on the hook only if first raised and turned sideways a predetermined amount.

2. A safety hook comprising a closed eye adapted for permanent engagement with a block eye, another eye beyond the first eye for engagement with a link at its bend, a con- 130

nection between and rigid with one side of the eyes, a relatively small hook below and extending in a plane substantially at right angles to the longitudinal plane of the connection and transversely thereof, and an extension from the second named eye on the side opposite to the connection to the lower end of the hook; said extension being spaced from the connection and from the upper end of the hook a distance greater than the thickness of a leg of the link and the upper end of the hook being similarly spaced from the connection.

3. A structure as in claim 2, in which the connection is curved about the upper portion of the hook on an axis disposed in the vertical plane of the hook on a radius smaller than that of the bend of the link.

In testimony whereof I affix my signature.
